US00D674193S

(12) **United States Design Patent**
Saavedra

(10) **Patent No.:** **US D674,193 S**
(45) **Date of Patent:** **** Jan. 15, 2013**

(54) **CLASP**

(75) Inventor: **Carlos Saavedra**, New York, NY (US)

(73) Assignee: **Henri Bendel, Inc.**, New York, NY (US)

(**) Term: **14 Years**

(21) Appl. No.: **29/403,057**

(22) Filed: **Sep. 30, 2011**

(51) **LOC (9) Cl.** **03-01**

(52) **U.S. Cl.** **D3/322**

(58) **Field of Classification Search** D3/232-233,
D3/240-246, 318, 322; 150/100, 103-110,
150/113-114, 117-119
